INTERCHANGEABLE INITIAL BELT BUCKLE

John R. Whitehouse and Harold C. Vaisey, Rochester, N. Y., assignors to Hickok Manufacturing Co. Inc., Rochester, N. Y., a corporation of New York

Application April 26, 1950, Serial No. 158,214

6 Claims. (Cl. 40—140)

1

This invention relates to belt buckles and more particularly to belt buckles that have associated with the face or front thereof interchangeable initials or letters or other indicia. Preferably, the belt buckle of the present invention is of the two-initial type and where the initials are interchangeable and detachably secured to the buckle. Additionally, the said initials or other indicia that are interchangeable with respect to the buckle are in the form of plaques or plates or the like which constitute the entire visible front surface of the buckle proper and the initials or letters are embossed or otherwise formed or placed on the plaques or plates. While two initials or letters on plates or plaques or the like are shown, it is understood that more than two such initials or letters may be utilized and that, if desired, one large plaque may be utilized and, in all instances, the plates or plaques which carry the initials or other indicia thereon constitute the sole visible front face of the buckle.

In our invention, as aforesaid, the initials or letters or other indicia are embossed, engraved or otherwise formed on and carried by a small plate or plaque, and each plaque carries at least one initial or letter thereon and, when two of such plates or plaques are used the same constitute the entire front visible face of the buckle. The plaques carrying the initials or letters, are associated with each other so that, from all outward visible appearances, the two plaques become as a unit so to speak and appear as one when viewed in elevation.

We preferably have the opposite side edges of the aforesaid plaques or plates that constitute the entire visible front face of the buckle inclined with respect to the vertical when viewed in elevation and the letters or initials carried by the said plaques are also preferably inclined with respect to the vertical but, obviously, if desired, the plaques may be made perfectly rectangular in outline with straight parallel opposite side and bottom and top edges. However, the inclination of the opposite sides of the plaques carrying the initials, letters or the like, presents a unique effect as will be seen from the description in detail hereinafter set forth.

In view of the foregoing, it is an object of our invention to provide a belt buckle wherein the entire visible front face thereof is in the form of an interchangeable and detachable plaque or plaques or plates and wherein the plaque or plate or plates has suitable indicia on the front surface thereof.

Another object of our invention is to provide

two initialed or lettered plaques, the opposite side edges of which are inclined with respect to the vertical and which plaques are readily associated with the buckle proper and detachably secured to and carried thereby.

Another object of our invention is to provide the interchangeable plaques carrying suitable indicia on the front face thereof and which plaques are readily handled by the retailer and are, likewise, readily secured to the buckle structure by simple sliding manipulation of the said plaques onto the buckle structure and providing means acting automatically to maintain the plaques in their proper association with the buckle structure.

With these and other objects in view, the invention consists in the construction and novel combination and arrangement of parts herein-after fully described, illustrated in the accompanying drawings and pointed out in the claims hereto appended, it being understood that various changes in the form, proportions, and minor details of construction, within the scope of the claims, may be resorted to without departing from the spirit or sacrificing any of the advantages of the invention.

In the drawings:

Fig. 1 is a view in perspective showing the buckle attached to one end of the belt and with the free end of the belt clamped in the buckle;

Fig. 2 is an exploded view of the major component elements of the buckle;

Fig. 3 is a front elevational view of the buckle attached to a belt and showing the angular or inclined disposition of the front initial panels of the buckle;

Fig. 4 is a rear elevational view of the buckle without the belt clamping means associated therewith;

Fig. 5 is a vertical sectional view taken substantially along the line 5—5 of Fig. 3 looking in the direction of the arrows;

Fig. 6 is a transverse sectional view taken substantially along the line 6—6 of Fig. 3 looking in the direction of the arrows;

Fig. 7 is a vertical sectional view taken substantially along the line 7—7 of Fig. 3;

Fig. 8 is a view in perspective showing the ratchet clamping means for the belt;

Fig. 9 is a modification of the invention in vertical section similar to the invention shown in Fig. 7; and

Fig. 10 is a perspective view of one element of the modifications of the invention as shown in Fig. 9.

The invention will be more readily understood

by referring to the drawings in detail wherein like reference numerals in the several figures of the drawings all denote the same parts.

The belt buckle denoted generally at B consists of a rear portion or element denoted generally at 10 and a face portion denoted generally at 11. The rear portion of the buckle is actually a channel-shaped frame and the buckle, as depicted in the drawings and modification is generally curved but, of course, may be carried out in a straight plane. The rear frame of the buckle is substantially rectangular in outline but, of course, may be of other shape and outline and includes a rear wall 12 which is preferably slightly curved from one end to the other. Medially of 15 and throughout the length of the curved rear wall, there is a raised platform 13 which extends from end to end of the buckle. This platform is spaced inwardly of the opposite side edges 14 and 15 of the buckle frame and thus provides oppositely disposed lower portions of the back plate 16 and 17, which said portions constitute the inner wall of a curved groove or slideway hereinafter more fully described.

The rear plate 12 has integral with the said lower side edge portions 16 and 17, right angularly extending spaced similarly formed flanges 18 and 19 respectively, these flanges emerging into elongated webs 20 and 21 which preferably taper or narrow in width from adjacent one end of the buckle to the other end thereof. These webs 20 and 21 are in spaced parallel relationship with the said rear wall 12 and form therewith a through passageway P in the buckle. The said webs 20 and 21 terminate short of one end of the buckle as indicated at 22 and 23 respectively and the ends of these webs 20 and 21 are formed into eyelets or bearings 24 and 25, which bearings are disposed opposite each other within the buckle and the same are in alignment and constitute the bearing or mounting means for the ratchet clamping means hereinafter described in detail. These said bearings 24 and 25 are formed simply by rolling around the free ends of the elongated and preferably tapering webs 20 and 21. The right-angularly disposed flanges 18 and 19 of the buckle frame also preferably taper in width from one end of the buckle to the other end and the taper being preferably opposite to the taper of the webs 20 and 21 that are attached thereto as clearly seen in Fig. 2 of the drawings.

The frame structure of the buckle is completed by means of a preferably rectangularly shaped initial carrying and slide or guideway forming wall 26, which substantially conforms in shape and size to the complete rear wall 12 of the buckle and, of course, this initial carrying wall 26 is curved similarly to the said rear wall of the buckle. This initial carrying wall 26 is positioned and registered on the said rear wall 12 of the buckle frame by means of spaced depressions 27 and 28 which register with similarly formed projections or protuberances 29 and 30 respectively on the outer portion of the rear wall 12. The wall is provided at one side edge portion thereof with an integral spring tongue T, which tongue extends slightly below the inner surface 31 of the initial carrying wall and serves to effectively lock the interchangeable plates or plaques in their proper association with the frame so as to constitute the entire visible front face of the buckle as herein-after described.

When the protuberances 29 and 30 are properly registered with the recesses or indentations 27 and 28, the initial carrying wall 26 will be prop-

erly registered and associated with the rear wall 12 of the buckle frame and this initial carrying wall 26 is preferably fixedly secured to the said rear wall 12 by soldering (not shown) or by welding, if desired, or secured in any other suitable manner.

Adjacent one end 32 of the initial carrying wall 26, and at a side edge thereof, there is struck out a downwardly extending abutment 33 which serves to limit the inward sliding movement of the first ornamented plate that is associated with the buckle frame structure. Only one such abutment 33 is shown but it is obvious that another abutment opposite the same may also be utilized, if desired, and, likewise, instead of utilizing only one of the spring tongues T, another of such tongues T may also be utilized at the other side of the initial carrying wall 26.

It will be seen, particularly from Fig. 7 of the drawings, that when the initial carrying and guide forming wall 26 is fixed to the raised or channel shaped medial portion 13 of the rear wall 12, opposite side edge portions 34 and 35 overlie the depressed or lowered portions 16 and 17 respectively of the said rear wall 12 and thus slightly curved grooves or guideways 36 and 37 are provided at opposite side edges of the buckle frame and these grooves or guideways are, of course, open at their side edges for a purpose later described.

The interchangeable plates or plaques O which have the letters or initials S or other indicia embossed or otherwise affixed or applied on the base portion 38 thereof, are substantially rectangular in outline and each of these plates, which are similarly formed except for the indicia on the face thereof, includes a base portion 38 which is preferably slightly recessed with respect to the preferably inclined edge border 39 which surrounds the same. The plates O are each provided with a right-angularly extending flange 40 at the top thereof and a similar flange 41 at the bottom thereof and these flanges each have integral therewith and at a right angle thereto, suitable spaced upper and lower tongues 42 and 43 respectively, and these tongues are in substantial parallelism with the face of the initialed or lettered plates O.

The opposite side edges 44 and 45 of the initialed or lettered plates are constituted by the inclined border or frame for the plates. As the initial structures are identical, only one of the same has been described in detail. It will be noted that the said inclined opposite side edges 44 and 45 are, in addition to the inclination with respect to the recessed base 38, also inclined with respect to the vertical so as to set off the display of the said plates or plaques, as clearly shown in Fig. 3 of the drawings, and it will be noted that, when two such initials are mounted on the buckle frame as in Fig. 3, the said inclined edges 44 and 45 abut each other as at A and it, therefore, gives the appearance of a single plate constituting the entire front face of the buckle as the line of demarcation between the abutted edges A is not discernible to the eye. Thus, a very unique display and appearance of the buckle is presented to the observer.

The individual plates carrying the initial, letter or other indicia thereon, as hereinbefore described, are very simply and readily and expeditiously attached to the buckle. All that is necessary is to align the tongues 42 and 43 with the open-sided grooves 36 and 37 respectively and slide these tongues in the said grooves until the

innermost tongue of the first plate or plaque that is applied engages the abutment 33 of the initial carrying guide or slide forming wall 26 as clearly seen in Fig. 6. When the second plate or plaque, with the initial or letter or other indicia thereon, likewise, has its tongues 42 and 43 aligned with the said grooves 36 and 37 respectively, the same is, by sliding movement, applied to the buckle frame and the portion of the free end of the spring tongue T in the wall 26 is so dimensioned and positioned that it will automatically snap behind the said tongue as shown at 46 in Figs. 6 and 7.

The buckle structure is completed by the combined ratchet or cam type belt clamping means denoted generally at C and includes an enclosed loop structure 47 to which one end of a belt is adapted to be secured, and the right-angularly extending preferably serrated belt gripping bar 48, and which ratchet or clamping element includes oppositely disposed vertically aligned pintles 49. These pintles 49 are so dimensioned and proportioned as regards their length and cross-sectional diameter as to be disposed and rotatably held in the bearings or eyes 24 and 25 that are formed at the ends of the tapered webs 20 and 21 respectively. As will be seen, particularly from Fig. 6 of the drawings, the ratchet clamping element C, when positioned and held in the bearings 24 and 25, is free to rotate therein and one end of the belt 50 is reversely bent upon itself as at 51 and is secured as by stitching indicated at 52 and this end, of course, surrounds the loop 47 and thus the said end of the belt is attached to the buckle or vice versa. The free end of the belt 53, and which preferably includes a point end 54, as seen in Figs. 1, 3 and 6, has been passed through the passageway P that is defined by the said spaced webs 20 and 21, and the inner portion of the rear wall 12; and, as seen in Fig. 6, the serrated bar 48 is in gripping relationship with the free end of the belt 53 and, thus, this free end is adjustably and detachably secured to the buckle or vice versa.

The buckle, as shown in the modification of the invention in Fig. 9, is quite similar in construction to the buckle as shown in the cross sectional view Fig. 7. In Fig. 9, however, the initial carrying or guide or slide forming wall 26 is the substantially channel shaped member and includes opposite raised side edge portions 55 and 56 and, of course, one or more spring tongues T are formed in the initial carrying wall 26 similar to the tongue or tongues T shown in the other figures of the drawing. Thus, the raised side edge portions 55 and 56 form, with the complementary side edge portions 57 and 58 respectively of the rear wall 12, the grooves 36 and 37, into which grooves the tongues 42 and 43 respectively of the ornamented plates or plaques O are adapted to enter and be secured therein as hereinbefore described in connection with the other figures of the drawings.

It will be seen that, when the plates with the ornamentation on the face thereof are associated with the frame of the buckle, in effect, the rectangular shaped initial carrying or guide or slide forming wall 26 actually supports these plates or plaques in a manner so that the plates or plaques constitute the entire visible front face of the buckle as clearly seen in Figs. 1, 3 and 7 and 9 of the drawings.

Additionally, and as shown in Fig. 10 of the drawings, the initial carrying wall 26 also includes the abutment 33 which serves the same

function and purpose as described hereinbefore.

The buckle and its modification, as described herein, is, of course, fabricated from metal. The initial carrying wall 26, it will be understood, is preferably made of a thinner gauge metal than the frame of the buckle and this metal possesses inherent resilient characteristics. Thus the tongues T are indeed resilient.

In order to release the ornamented plates or 10 plaques that are locked in engagement with the frame of the buckle, there is provided an opening U in the buckle frame which is disposed directly beneath and in alignment with the free spring 15 end of the tongue T and, by inserting a small pin or rod or the like through this opening U, the spring tongue T can be raised from its engagement with one of the tongues 42 or 43 as the case may be and thus the ornamented plate is released and can be readily slid off of the frame.

20 We claim:

1. A belt buckle comprising a main frame member including a rectangular shaped rear plate, an ornamental plate carrying rectangular shaped plate of substantially the same size as said rear plate secured thereon at the front side thereof in opposed face to face relation therewith, said plates having oppositely disposed spaced upper and lower marginal portions forming longitudinally extending grooves, an ornamental plate 25 slidably mounted on said ornamental plate carrying plate, said ornamental plate having at the upper and lower edges thereof flanges extending rearwardly at substantially a right angle thereto, said flanges having inwardly extending spaced 30 tongues integral therewith slidably engaging in said grooves, a stop portion on the ornamental plate carrying plate near one end thereof engaging one of said tongues and limiting longitudinal sliding movement of the ornamental plate 35 in one direction, and a spring tongue on the ornamental plate carrying plate projecting rearwardly therefrom into one of said grooves and adapted to engage one of said tongues to hold the ornamental plate in position on the plate carrying plate.

2. A belt buckle comprising a main frame member including a rectangular shaped rear plate, an ornamental plate carrying rectangular shaped plate of substantially the same size as said rear plate secured thereon at the front side thereof in opposed face to face relation therewith, said plates having oppositely disposed spaced upper and lower marginal portions forming longitudinally extending grooves, an ornamental plate 50 slidably mounted on said ornamental plate carrying plate, said ornamental plate having at the upper and lower edges thereof flanges extending rearwardly at substantially a right angle thereto, said flanges having inwardly extending spaced 55 tongues integral therewith slidably engaging in said grooves, a stop portion on the ornamental plate carrying plate near one end thereof engaging one of said tongues and limiting longitudinal sliding movement of the ornamental plate 60 in one direction, and a spring tongue on the ornamental plate carrying plate projecting rearwardly therefrom into one of said grooves and adapted to engage a side edge of one of said tongues to hold the ornamental plate in position on the plate carrying plate.

3. A belt buckle comprising a main frame member including a rectangular shaped rear plate, an ornamental plate carrying rectangular shaped plate of substantially the same size as said 70 rear plate secured thereon at the front side there-

of in opposed face to face relation therewith, one of said plates having upper and lower longitudinally extending marginal portions offset laterally from the plane of the major part thereof and away from the corresponding opposing upper and lower marginal portions of the other plate and forming therewith upper and lower grooves, an ornamental plate slidably mounted on said ornamental plate carrying plate, said ornamental plate having at the upper and lower edges thereof flanges extending rearwardly at substantially a right angle thereto, said flanges having inwardly extending spaced tongues integral therewith slidably engaging in said grooves, a stop portion on the ornamental plate carrying plate near one end thereof engaging one of said tongues and limiting longitudinal sliding movement of the ornamental plate in one direction, and a spring tongue on the ornamental plate carrying plate projecting rearwardly therefrom into one of said grooves and adapted to engage one of said tongues to hold the ornamental plate in position on the plate carrying plate.

4. A belt buckle comprising a main frame member including a rectangular shaped rear plate, an ornamental plate carrying rectangular shaped plate of substantially the same size as said rear plate secured thereon at the front side thereof in opposed face to face relation therewith, the rear plate having upper and lower depressed marginal portions spaced from the corresponding opposing marginal portions of the ornamental plate carrying plate and providing therewith upper and lower grooves, an ornamental plate slidably mounted on said ornamental plate carrying plate, said ornamental plate having at the upper and lower edges thereof flanges extending rearwardly at substantially a right angle thereto, said flanges having inwardly extending spaced tongues integral therewith slidably engaging in said grooves, a stop portion on the ornamental plate carrying plate near one end thereof engaging one of said tongues and limiting longitudinal sliding movement of the ornamental plate in one direction, and a spring tongue on the ornamental plate carrying plate projecting rearwardly therefrom into one of said grooves and adapted to engage one of said tongues to hold the ornamental plate in position on the plate carrying plate.

5. A belt buckle comprising a main frame member including an elongated rectangular shaped rear plate, an ornamental plate carrying elongated rectangular shaped plate of substantially the same size as said rear plate secured on said rear plate at the front side thereof in opposed face to face relation therewith, said plates having oppositely disposed spaced upper and lower marginal portions forming longitudinally extending grooves, a plurality of ornamental plates slidably mounted on said ornamental plate carrying plate, with the opposing side edges of the ornamental plates fitting one against the other, each of said ornamental plates having at the upper and lower edges thereof flanges ex-

tending rearwardly at substantially a right angle thereto, said flanges having inwardly extending spaced tongues integral therewith slidably engaging in said grooves, a stop portion on the ornamental plate carrying plate near one end thereof cooperating with one of said tongues of one of the ornamental plates and limiting longitudinal sliding movement of the same in one direction, and a spring tongue on said ornamental plate carrying plate projecting rearwardly therefrom into one of said grooves adapted to engage one of the tongues of one of the ornamental plates to hold the ornamental plates in position on said plate carrying plate.

15 6. A belt buckle comprising a main frame member including an elongated rectangular shaped rear plate, an ornamental plate carrying elongated rectangular shaped plate of substantially the same size as said rear plate secured on said rear plate at the front side thereof in opposed face to face relation therewith, said plates having oppositely disposed spaced upper and lower marginal portions forming longitudinally extending grooves, a plurality of ornamental plates slidably mounted on said ornamental plate carrying plate, said ornamental plates each having parallel inclined side edges and each ornamental plate having a letter on the front side thereof disposed at an inclination corresponding to the 20 inclination of the side edges of the ornamental plate, the opposing inclined side edges of the ornamental plates fitting one against the other, said ornamental plates constituting the entire visible front face of the buckle when viewed in 25 elevation, each of said ornamental plates having at the upper and lower edges thereof flanges extending rearwardly at substantially a right angle thereto, said flanges having inwardly extending spaced tongues integral therewith slidably engaging in said grooves, a stop portion on the ornamental plate carrying plate near one end thereof cooperating with one of said tongues of one of the ornamental plates and limiting longitudinal sliding movement of the same in one direction, and a spring tongue on said ornamental plate carrying plate projecting rearwardly therefrom into one of said grooves adapted to engage one of the tongues of one of the ornamental plates to hold the ornamental plates in position 30 on said plate carrying plate.
